UNITED STATES PATENT OFFICE.

EDWARD O. SCRIVEN, OF NEW YORK, N. Y., ASSIGNOR TO WESTERN ELECTRIC COMPANY, INCORPORATED, OF NEW YORK, N. Y., A CORPORATION OF NEW YORK.

SIGNALING BY HIGH-FREQUENCY WAVES.

Application filed September 29, 1919. Serial No. 327,038.

To all whom it may concern:

Be it known that I, EDWARD O. SCRIVEN, a citizen of the United States, residing at New York, in the county of New York, State of New York, have invented certain new and useful Improvements in Signaling by High-Frequency Waves, of which the following is a full, clear, concise, and exact description.

The present invention relates to the transmission and control of current waves for signaling or other purposes. The invention relates also to multiplex transmission of the type employing current waves of different frequencies each of which waves is controlled in accordance with signals or other impulses to be transmitted.

A feature of the invention lies in an improved modulating arrangement. Another feature lies in providing a centralized source of high frequency waves and method and means whereby waves from said source are controlled to effect multiplex transmission in both directions over a line or similar system.

In systems heretofore used it has been customary to impress a high frequency wave and low frequency signaling currents separately upon a control device or modulator, and in another circuit suitably associated with the modulator to derive the combination frequencies. The only high frequency waves impressed on the line or transmission circuit in the process of transmission were those transmitted through the modulator itself.

In the present invention the same circuit which impresses the high frequency currents upon the modulator may serve to convey the modulated currents to the line or common transmission circuit, and it is not necessary, therefore, to provide a source of high frequency waves from a separate high frequency circuit for each modulator distinct from the circuit for carrying the modulated waves. The high frequencies are impressed from the generating sources upon the line or common transmission circuit, and each modulator derives its supply of high frequency from the line or common transmission circuit and feeds back through the same circuit the modulated current when the signaling currents are also impressed upon the modulator. By associating the high frequency sources with the line or common transmission circuit instead of with the separate modulators the present invention makes

possible the use of centralized sources of high frequency waves for supplying a number of modulators. These wave sources may be located at some convenient point on the line and at a distance, if desired, from the transmitting sets to which they supply energy.

Other features and objects of the invention will appear from the following description together with the accompanying drawings, of which Figs. 1 and 2, when placed side by side, illustrate diagrammatically a complete two-channel high frequency telephone system, and Fig. 3 shows a modified arrangement.

Referring first to Figs. 1 and 2, the main line 1 is shown as terminating at two stations, one of which has transmitting sets T_1 and T_2 , and receiving sets R_3 and R_4 , and the other of which has sets R_1 and R_2 , and T_3 and T_4 , cooperating respectively with the transmitting and receiving sets of the first station. For enabling simultaneous two-way communication, the line 1 is provided with the usual conjugate coils 4 and 5 and the balancing or net-work circuits for these coils indicated at 2 and 3 respectively. A source of high frequency waves 6, of frequency preferably near but above the highest essential voice frequency, is provided for furnishing the energy of all of the high frequency waves employed in the system illustrated. The generator circuit includes coils 7 and 8 for deriving energy from the source 6.

Coupled to the coil 8 is a thermionic relay 9 of usual construction which serves as a distorting relay for enabling the generation of harmonics from the base frequency wave from source 6. The distorted and amplified wave from the relay 9 is transmitted through the coupling 10 and impressed upon the amplifier 11, the output circuit of which includes the resonant circuits 12 and 13. In the case of a system employing more than two communication channels, additional circuits similar to 12 and 13 would be provided for deriving still other harmonics from the base frequency wave. Individual amplifiers 14 and 15 are provided for the harmonic waves which are selected by the circuits 12 and 13 respectively.

Coupled to the amplifiers 14 and 15 are the coils 16 and 17 which are included serially with a coil 18 coupled to the coil 7 in the cir-

cuit of source 6 and the circuit including coils 16, 17 and 18 is finally connected across the terminals of the output line winding 4. Between the coil 18 and the remainder of the 5 circuit there is inserted a filter 19 so proportioned as to transmit only the base frequency current from the source 6, and to prevent frequencies impressed upon coils 16 and 17 from reacting on the circuit of source 10 6. There are, therefore, waves of three different frequencies simultaneously impressed upon the main line 1, one of which waves is the wave directly transmitted from the source 6 and the other two of which have 15 frequencies which are harmonics of the base frequency. Also connected across the terminals of the input coil of the line coupling 4, are filters 20 and 21. The filter 20 is designed to admit to the coil 22 a band of frequencies sufficient in breadth to include one 20 of the high frequency waves impressed on the input coil 4, together with the side bands of frequencies which result from modulating said wave in accordance with speech. 25 For the particulars relating to the design and construction of such a filter reference may be had to the patent to G. A. Campbell No. 1,227,113, issued May 22, 1917. This filter prevents currents of all other frequencies 30 from reaching the coil 22 on account of the highly attenuating property which it possesses for foreign frequencies. One of the high frequency waves which was impressed on the main line 1 from amplifiers 35 14 or 15 is therefore transmitted to the coil 22 by the filter 20, and by virtue of the coupling with the coil 23 sets up corresponding voltages across the terminals of coil 23. The latter coil is included in the output or 40 plate circuit of the modulator M_1 which also includes the plate battery shown, the cathode 24 and the plate or anode 25. Due to the potential variations induced in the coil 23, there will be a current flow in the output 45 circuit of the modulator M_1 , the magnitude of which current will depend upon the impedance of this circuit. Practically the whole of this impedance lies in the modulator tube itself, and this impedance, in turn, 50 depends upon the potential of the grid 26 which is determined by voice currents in the circuit 27 due to speech waves directed against the microphone 28. By speaking into the microphone 28, which forms a part 55 of the transmitting set T_1 , variable currents of the frequency of the wave admitted by the filter 20 from the main line 1 will be set up in the output coil 23 and will be impressed through the filter 20 upon the line 1. 60 The action of the modulator M_1 is apparently the same as though the high frequency waves were impressed upon the plate circuit through a separate coupling, but by virtue of the present arrangement no such separate 65 coupling is needed, and, as stated, the high

frequency may be derived from the transmission line itself.

The transmitting set T_2 differs from that just described only in the frequency of the wave which is employed for transmission; that is, the filter 21 is so proportioned as to transmit a different high frequency voice modulated wave. The modulated high frequency waves from the modulators M_1 and M_2 are, therefore, impressed through the 75 coupling 4 upon the main line 1 and are transmitted to the distant station indicated in Fig. 2. Bridged across the line at this station is the coil 30 to which are coupled filters 31, 32 and 33, which are or may be 80 identical respectively with the filters 19, 20 and 21, shown at the transmitting station. Frequencies from the transmitting sets impressed upon the coil 30 are, therefore, selectively transmitted by the filters 32 and 33, 85 associated with which are the detectors D_1 and D_2 respectively. These serve to detect the speech component of the modulated waves and render the waves receivable respectively in the telephone receiver's 34 and 90 35.

The filters 20, 21, 31, 32, 33, F_3 and F_4 are each composed of a plurality of sections. The end sections of filters 20 and 21, which are adjacent to the common line 1, are connected together in series with respect to line. These end sections form paths of low impedance to currents of all frequencies except those which the filter is designed to pass. Similarly the end sections of filters 31, 32 100 and 33 as a group and those of filters F_3 and F_4 as a group are connected together in series.

As already stated, the source 6 supplies energy for all of the high frequency waves 105 used to transmit in both directions through the system being described. For transmitting in the direction opposite to that above described, two waves, which may or may not have the same frequencies as those employed by the transmitters T_1 and T_2 , are derived from the same source 6. The wave of base frequency transmitted over the line is selectively transmitted through the filter 31, as described, and is impressed upon the 110 distorting relay 36 for the purpose of producing harmonics. Coupled to the distorting relay 36 is an amplifier 37 containing in its output circuit the resonant circuits 12' and 13' respectively, and these are coupled 115 to the separate amplifiers 38 and 39, which supply the amplified currents of harmonic frequencies through the coils 40 and 41 to the output line coil 5. The transmitting sets T_3 and T_4 are associated through the respective modulators M_3 and M_4 , and the band filters F_3 and F_4 with the main line in a similar manner to that described in connection with the transmitting sets T_1 and T_2 . If the same harmonics are employed 125 130

for transmission in both directions, the filters F_3 and F_4 may be identical with the filters 20 and 21. The modulated waves from the transmitting sets T_3 and T_4 are impressed upon the main line 1, and are received at the station, shown in Fig. 1, where they are separated by the filters F_3 and F_4 to be separately received. The detectors D_3 and D_4 render the wave receivable in the receivers shown for the receiving sets R_3 and R_4 , respectively.

By virtue of the conjugate arrangements of the coils 4 and 5 and corresponding nets 2 and 3, the modulated waves produced in each station are prevented from affecting the receiving sets located in the same station, according to standard practice.

Referring now to Fig. 3, there is shown a main line 42 which may be provided with 20 branches 48 and 49, as may be desired. The main line is shown as provided with conjugate coils 43 and net-work 44 and the branches may be similarly provided. At 25 some convenient point on the main line 42, for instance in a central station, may be located the wave sources 45, 46 and 47 having frequencies f , f' and f'' , which sources may be separated or may be related in some such way, as described in connection with the 30 other figures. These sources supply waves of their respective frequencies to the main line 42, which waves are made available for all of the transmitting sets located upon the line. A part of the energy of each wave 35 will find its way into the transmitting and receiving side of the station shown at the left of the line. The band filters diagrammatically indicated as F , F' and F'' serve to convey to the respective modulators the 40 waves that are to be utilized by the transmitting sets, three of which are indicated. Modulated high frequency currents from these modulators M , M' and M'' are in turn impressed through the coils upon the main 45 line 42, and may be received at such of the distant stations indicated on the respective branches 48 and 49 as are adapted to receive and detect it. The balanced relation between the transmitting and receiving sides 50 of each station, however, will prevent the modulation component, resulting from the interaction of each high frequency wave with the signaling currents, from reaching the receiving side of the same station. 55 Modulated waves impressed upon the line at another station, however, will, in the usual manner, be impressed through the filters F , F' and F'' upon the detectors D , D' and D'' and will be received in the respective 60 receivers.

While the invention has been illustrated and described with reference to a particular circuit arrangement, it is to be understood that it is not to be construed as limited to 65 the circuit arrangements, as a whole, or to

the specific details, but only by the scope of the appended claims.

What is claimed is:

1. In a signaling system, a line, means for impressing on said line a plurality of high-frequency waves of different frequencies, and means for modulating each of said waves in accordance with signals to be transmitted over said line, the modulating means for each of said waves comprising a modulator, a band filter for diverting one of said waves from the line to said modulator, a coupling for impressing said wave upon said modulator, a circuit for also impressing signaling current on said modulator to modulate said high-frequency wave, said coupling and selective circuit serving also to impress the modulated wave upon said line. 70

2. In a signaling system, a line, a source of high-frequency waves supplying waves to said line, and means for impressing signal-modulated high-frequency waves upon said line, said means comprising a modulator having an input circuit for signaling current and an output circuit both for the high-frequency waves to be modulated and for the high-frequency waves modulated in accordance with said signaling current, a band filter connected between said output circuit and said line, whereby said high frequency waves are applied to said output circuit from said line through the medium of said band filter. 80

3. In a signaling system, a line, a source of high-frequency waves for supplying current thereto, a modulator for controlling said waves in accordance with signals, means to connect said source of waves to said line, and a band filter connected between said means and said modulator for transmitting selectively said waves to said modulator and the signal-modulated wave from said modulator to said line. 90

4. In a telephone system, a line, a source of sustained high-frequency waves for supplying current to said line, a modulator having means whereby speech variations may be impressed thereon for modulating said high-frequency waves, means to connect said source of waves to said line, and a band filter connected between said modulator and said means for impressing said waves upon said modulator to be modulated in accordance with speech and for transmitting the speech modulated waves from said modulator to said line. 110

5. A high-frequency wave signalling system comprising a line having stations, transmitting and receiving branches for said line at a station, and conjugate connections for making the receiving branch neutral as to current impressed from the transmitting branch, sources of high frequency waves for supplying current to said line, modulators associated with said transmitting branch 120

- and controlled by signals, means to connect said sources to said line, band filters connected between said modulators and said means, each adapted both for impressing 5 said waves upon the respective modulators and for transmitting the resultant modulated waves from said modulators to said line, and receivers at another station for the waves so modulated.
- 10 6. In a signaling system, a line, a plurality of sources of high-frequency waves for supplying current to said line, a plurality of modulators for controlling said waves in accordance with signals, and a plurality of 15 sectional band-pass filters connected between said modulators and said line, the end sections of said band-pass filters being connected in series with each other.
- 20 7. In a telephone system, a line, a plurality of sources of sustained high-frequency waves for supplying current to said line, a plurality of modulators having means whereby speech variations may be impressed thereon for modulating a high-frequency 25 wave, and a plurality of sectional band-pass filters between said modulators and said line, the end sections of said band-pass filters being connected in series with each other.
- 30 8. In a signaling system, a line, a plurality of sources of high-frequency waves for supplying current to said line, a plurality of modulators for controlling said waves in accordance with signals, and a plurality of 35 sectional band-pass filters, one of said filters being connected between said line and each modulator for transmitting selectively a high-frequency wave to said modulator and a signal modulated wave from said modulator to said line, the end sections adjacent to said line of all of said filters being connected in series with each other.
- 40 9. In a telephone system, a line, a source of sustained high-frequency waves for supplying current to said line, a modulator having means whereby speech variations may be impressed thereon for modulating a high-frequency wave, and a plurality of sectional band-pass filters, one filter being connected 45 between each modulator and said line for impressing a high-frequency wave upon said modulator to be modulated in accordance with speech and for transmitting the speech modulated wave from said modulator to said line, the end sections of said filters adjacent to said line being connected in series with each other.
- 50 10. A high-frequency wave signaling system comprising a line having stations, a plurality of transmitting and a plurality of receiving branches for said line at said station and conjugate connections for making the receiving branches neutral as to current impressed from the transmitting branches, a 55 plurality of sources of high-frequency 60 waves for supplying current to said line, a modulator associated with each of said transmitting branches and controlled by signals, a sectional band-pass filter between each modulator and said line adapted both for impressing said waves upon the respective modulators and for transmitting the resultant modulated waves from said modulator to said line, the end sections of said filters adjacent to said line being connected in series with each other, and receivers at another station for the waves so modulated.
- 65 11. A high-frequency wave signaling system comprising a line having stations, a plurality of transmitting and a plurality of receiving branches for said line at a station and means to connect said transmitting and receiving branches to said line, a plurality of sources of high-frequency waves for supplying current to said line, a modulator associated with each transmitting branch and controlled by signals, a sectional band-pass filter connected between said modulator and said line adapted both for impressing said waves upon the connected modulator and for transmitting the resultant modulated waves from the connected modulator to the line, means to connect the end sections of said filters adjacent to said line in series with each other, and receivers at another station for the waves so modulated.
- 70 12. In a multiplex signaling system, a plurality of sources of high-frequency waves, a plurality of means to modulate said high-frequency waves in accordance with signals, a common transmission circuit, and a band-pass filter connected between each modulating means and said transmission circuit comprising a plurality of sections, the end sections being connected in series with each other.
- 75 13. In a multiplex signaling system, a plurality of sources of high-frequency waves, a plurality of means to modulate said high-frequency waves in accordance with signals, a common transmission circuit, a sectional band-pass filter connected between each modulating means and said transmission circuit, and means to connect the end sections adjacent to said transmission circuit in series with each other.
- 80 14. In a multiplex signaling system, a plurality of sources of high-frequency waves, a plurality of thermionic vacuum tubes each having an anode, a cathode and an impedance controlling element or grid, a source of signaling current, means to supply said high-frequency current and said signaling current simultaneously to said vacuum tubes to produce high-frequency current modulated in accordance with signaling current, a common transmission circuit, a sectional band-pass filter connected between each vacuum tube modulator and said transmission circuit, and means to con-
- 85 90 95 100 105 110 115 120 125 130

nect the end sections nearest said transmission circuit together in series.

15. A common transmission circuit, a plurality of channels associated therewith, means for transferring currents of a given range of frequencies between one of said channels and said circuit and currents of a different range of frequencies between each of the other channels and said circuit 10 comprising a band filter connecting each channel to said circuit and having a transmission range such that it freely passes currents of the range of frequencies supplied from the associated channel, said band filters 15 having terminations connected in series in said circuit, the termination of each filter offering low impedance to currents within the frequency transmission range of the other filters.
20. 16. A common transmission path, a plurality of channels each adapted to transmit currents of different frequency from those transmitted by the other channels, and a separate band filter connecting each channel to said path, the terminations of said filters electrically adjacent said path being connected in series.
25. 17. In a modulating circuit, an electric discharge modulator tube having an anode, a cathode and a grid or impedance control element, a circuit for impressing signal variations across the grid and cathode of
30. 35. 40. 45. 50. 55. 60. said tube, a source of waves to be modulated, a circuit for impressing waves from said source across the anode and cathode of said tube, a band filter included in said latter circuit having a selective transmission range such as to include the frequencies of the waves to be modulated and at least a portion of the resulting signal-modulated components, and an outgoing circuit for the modulated wave connected to said modulator tube through said filter.
18. In a modulating circuit, an electric discharge tube modulator having an anode, a cathode and a grid or impedance control element, means to impress speech variations across the cathode and grid, a source of waves to be modulated, a band filter having a selective frequency transmission range such as to include the frequency of the wave from said source and at least a portion of the frequency components of the resultant modulated wave, but excluding speech frequencies, a circuit including said band filter for impressing waves from said source across the anode and cathode of said tube, and an outgoing circuit for the modulated wave connected to said modulator through said filter.

In witness whereof, I hereunto subscribe my name this 26th day of September A. D., 1919.

EDWARD O. SCRIVEN.
